UNITED STATES PATENT OFFICE.

ROBERT B. CARSLEY, OF CHELSEA, MASSACHUSETTS.

DESIGN FOR A HAND-STAMP.

Specification forming part of Design No. 5,133, dated July 25, 1871.

To all whom it may concern:

Be it known that I, ROBERT B. CARSLEY, of Chelsea, in the county of Suffolk, and State of Massachusetts, have invented and produced a new and original Design for an Embossing Hand-Stamp; and do hereby declare the nature thereof to be fully described in the following specification and represented in the accompanying drawing or cut.

My said design consists of a buffalo represented as kneeling or resting with his front legs folded upon the intaglio or upper die-plate, while his hind legs are embedded in a mass of shrubbery or grass springing up from the base-plate of the stamp. Furthermore, the hind legs of the buf-

falo are pivoted to the said base-plate, a curved spring affixed to the rear part of the animal and the base-plate serving to restore the upper die to the position shown after each downward movement thereof.

The dies, arranged as shown, are of a truncated oval shape in horizontal section.

Having described my invention, what I claim is—

The design for an embossing hand-stamp, substantially as described and shown.

R. B. CARSLEY.
